PAIR OF PLIERS

Jacob Sackstein, Portsmouth, Va.

Application July 23, 1953, Serial No. 26,110

Term of patent 14 years

(Cl. D54—13)

FIG-1-

FIG-2-

FIG-3-

Figure 1 is a side elevation of the pair of pliers, showing my new design;

Figure 2 is a top plan view of the full line portion of Figure 1; and

Figure 3 is a side elevation view of the opposite side of the full line portion of Figure 1.

The dominant features of my design reside in the portions shown in the full lines.

I claim:

The ornamental design for a pair of pliers, as shown and described.
